UNITED STATES PATENT OFFICE.

THOMAS B. ATTERBURY, OF PITTSBURG, PENNSYLVANIA.

DESIGN FOR A TUREEN OR DISH.

SPECIFICATION forming part of Design No. 16,558, dated March 9, 1886.

Application filed January 26, 1886. Serial No. 1-9,850. Term of patent 7 years.

To all whom it may concern:

Be it known that I, THOMAS B. ATTERBURY, a citizen of the United States, residing at Pittsburgh, in the county of Allegheny and State of Pennsylvania, have invented and produced a new and original Design for a Tureen or Dish; and I do declare the following to be a full, clear, and exact description of the same, reference being had to the accompanying drawing, forming a part thereof.

In the drawing I have shown in side elevation a covered dish or tureen, which represents a rabbit in a sitting or crouching position. The leading feature of my design consists in a dish having an oblong body following the configuration of a rabbit in shape, which is divided horizontally and longitudinally into two parts, the upper portion forming the cover of the dish or tureen.

In the drawing, A is the lower part of the dish or tureen, and represents the lower portion of a rabbit in a sitting or crouching po-

sition, the division-line between the upper and lower portions being taken through between the upper and lower jaws of the animal. The feet and legs, being partially under the body, are the support or base of the dish.

B is the cover, in the form of the upper portion of a rabbit, with the upper portion of the head and the ears.

C are the ears of the rabbit, and project rearward from the head along the back of the animal.

What I claim is—

A design for a dish or tureen having the body A and cover B, the whole representing the conventional configuration or shape of a rabbit *en couchant*, as shown and described.

In testimony whereof I affix my signature in presence of two witnesses.

THOMAS B. ATTERBURY.
